UNITED STATES PATENT OFFICE.

ARTHUR JEFFERY, OF HAYWARDS HEATH, ENGLAND.

PAYING APPARATUS.

SPECIFICATION forming part of Letters Patent No. 761,303, dated May 31, 1904.

Application filed June 10, 1903. Serial No. 160,872. (No model.)

To all whom it may concern:

Be it known that I, ARTHUR JEFFERY, a subject of the King of England, and a resident of Muster Green, Haywards Heath, Sussex, England, have invented a new and useful Improvement 5 in Paying Apparatus, of which the following is a specification.

My invention relates to paying-machines for decks or floors.

10 The object of the invention is to provide a machine adapted to run over decks or floors and automatically pay or glue the seams of the same. In its operation the paying material is melted only as fast as desired and delivered to the seams in regulated quantities.

15 For accomplishing these purposes my invention consists in the following construction and combination of parts, the details of which will first be fully set forth and described, and 20 the features of novelty then set forth and claimed.

Figure 1 represents the side elevation of a machine to which these improvements have been applied. Fig. 2 is a detached end view 25 of the reservoir containing the paying material. Fig. 3 is a longitudinal sectional view of the machine with the lamp or burner removed. Fig. 4 is a transverse sectional view of the machine and longitudinal section of the 30 delivery-spout. Fig. 5 is a detached plan broken away of the outer end of the operating-handle.

In the description of the invention the word "deck" will be employed to designate any 35 deck or floor.

The machine comprises a frame 1, mounted on wheels 2. The wheel or wheels on the side of the machine in line with the delivery-spout are provided with flanges 3, which are adapted 40 to run in the seams of the deck for the purpose of accurately guiding or alining the delivery-spout along the line of the seam being treated. Upon the frame is mounted a combustion or burner chamber 4, provided with an intake 5 for the burner and an exit-opening 6, preferably provided with a baffle-plate 7. The top of the combustion-chamber 4 is open to receive a reservoir 8, holding paying material. The cover 9 of the reservoir 4 is generally cast with the reservoir 8, as shown; but

it is obvious that it may be made separate and the reservoir fit within the cover, so as to be supported thereby. Reservoir 8 is provided with a cover 10, through which the paying material is inserted.

55 Intermediate of and preferably near the bottom of reservoir 8 is provided, preferably, a horizontal support 11 for the solid paying material, such as marine glue. In this instance the support is composed of a series of tubes 60 extending longitudinally of the reservoir 8 and opening through the same at opposite ends. The essential feature of this support is that it shall be provided with an opening or openings through which the paying material 65 as it becomes heated and fluid or viscous may pass downwardly and out of the delivery-spout. The bottom of reservoir 8 is preferably inclined, as shown, to afford facility for cleaning the same, a cleaning door or opening 70 12 being provided, preferably lined with asbestos. Below the support or supports 11 is an auxiliary perforated screen or scavenger-plate 13, adapted to intercept any impurities or extraneous matter in the paying material 75 which would have the tendency to clog the valve in the delivery-spout. This scavenger-plate is made removable, the door 12 and removable baffle-plate being of sufficient dimensions to admit of its being removed through 80 the same and replaced.

The intake 5 is provided with an elongated slit 14 for securing an adequate supply of air for the burner.

Instead of cleaning the bottom of the reservoir 8 through the baffle-plate opening the reservoir 8 and the cover 9 may be removed upwardly and the interior thereby made accessible.

85 15 is a division-plate adapted to intercept the products of combustion from the burner and divide the same, throwing them partly through the tubes 11 and partly under the reservoir 8.

The discharge-spout 16 communicates with the bottom of the reservoir 8 and inclines to 95 one side in order to deliver the melted paying material in the line of the flanges 3 on the wheels 2. The discharge end of spout 16 is preferably narrowed in somewhat, as shown in Figs. 1 and 4, and a tubular valve-chamber 100

17 inclosed therein. Spout 16 connects with the interior of the valve-chamber 17. Rod 18 is adapted to reciprocate in valve-chamber 17, and the outer end of the same constitutes a 5 cut-off or valve for controlling the supply of the viscous paying material. The reciprocation of the plunger in the valve acts to clean the valve, and when the paying material is cold the end of the plunger acts as a shear to 10 cut out and clear any material which may be in the valve.

Surrounding the delivery-spout 16 is a 15 downwardly-projecting flue 19, forming a concentric flue-space around the spout. Flue 19 is preferably secured rigidly to the delivery-spout by spider-frames 20, and removable connection is made between the spout and the bottom of the reservoir 8, preferably by a 20 tight ground-joint connection, and the flue 19 is secured to the combustion-chamber 4, preferably by a bayonet-joint 21. This construction permits the insertion and removal of the 25 spout 16 in the bottom of the reservoir and the oscillation of it and the flue 19 sufficiently to effect the bayonet-lock.

Rod 18 in its reciprocation is supported at one end in the valve-chamber and at the other in a bracket 22.

23 is an arm rigidly connected to the machine at some point, such as the intake, by a connection 24, and its outer end is provided with a handle 25. Connected to the reciprocating valve-rod 18 is a link 26, extending up alongside the arm 23 and having its outer end 30 connected with a valve operating a handle 27 and consisting of a rod 28 and a connection 29, preferably pivotal. A universal joint 30 of some approved type is preferably used to connect the reciprocating valve-rod 18 with 35 the handle 27, whereby the operator may with one hand draw the machine along the seams of the deck and with a finger or fingers of the same hand manipulate the valve-rod 18 through the handle 27.

40 The burner 31 may be of any approved construction. In this instance I have shown a burner of the Bunsen type with a reservoir 32, pump 33, and handle 34, supported upon a frame 35, carried by the frame 1. It is obvious, however, that any other type of support and lamp may be employed.

While I have described the pump-support 11 for the paying material composed of fire-tubes passing through the reservoir 8, it will be 45 understood that any other type or form of reticulated support may be used. The wheels 2 are preferably of wood or other non-conducting material with metal rims.

It will be noted that the entire machine is 50 located to one side of the flanged wheels 3 in order that the operator in using the machine may observe the progress of the work

of the machine during its operation. The machine is preferably drawn toward the person operating it, and the delivery of the melted 65 paying material trails the flanged wheels the latter entering the seams of the deck, guiding the machine. Moreover, by arranging the machine at one side of the flanged wheels the 70 seams of the deck next the rails, hatchways, copings, and the like may be paid without the machine encountering any obstructions.

The products of combustion are divided between the flue-supports 11 and the bottom of the combustion-chamber, a portion of the 75 heat passing out around or through baffle-plate 7 and a portion passing downwardly around the discharge-spout 16 and in contact with the valve-chamber 17, thereby keeping the paying material fluid or viscous in the 80 valve and permitting it to flow freely through the same.

What I claim is—

1. In a paying-machine the combination of 85 a combustion-chamber and reservoir therein having an intermediate support in the reservoir, a scavenger-plate located below said support, and a delivery-spout, a burner and a movable frame supporting the machine.

2. In a paying-machine, the combination of 90 a combustion-chamber having a downwardly-projecting flue, a reservoir carried by the combustion-chamber having a discharge-spout concentric with said flue, said reservoir being provided with an intermediate support for the 95 paying material and a division-plate for dividing the products of combustion through said support and under the reservoir.

3. In a paying-machine, the combination of 100 a movable frame, a combustion-chamber and a detachable reservoir carried thereby, a discharge-spout for the reservoir projecting downwardly through the combustion-chamber, and detachably connected to the reservoir, 105 whereby the reservoir and combustion-chamber may be separated for cleaning.

4. In a paying-machine, the combination of 110 a movable frame, a combustion-chamber and a reservoir carried thereby, and a detachable downwardly-projecting spout and flue communicating with the reservoir and combustion-flue respectively.

5. In a paying-machine, the combination of 115 a movable frame, a combustion-chamber carried thereby, a reservoir carried by the combustion-chamber, and a cover for the combustion-chamber secured to the sides of the reservoir.

In testimony whereof I have affixed my signature in the presence of two witnesses.

ARTHUR JEFFERY.
